UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

COMMODITY-CABINET.

1,351,464.

Specification of Letters Patent. Patented Aug. 31, 1920.

Application filed November 29, 1919. Serial No. 341,363.

To all whom it may concern:

Be it known that I, JAMES H. BOYE, a citizen of the United States, residing at Chicago, in the county of Cook and State 5 of Illinois, have invented certain new and useful Improvements in Commodity-Cabinets, of which the following is a specification.

This invention relates to an improved 10 commodity cabinet of the kind extensively used in dry goods stores for containing small articles of merchandise which are usually put up in packages of uniform size, such, for instance, as sewing machine parts and 15 accessories. In its principal intended use, the cabinet of my present invention is designed for the containing and dispensing of plain and sewing machine needles which, as is well known, are usually put up for the 20 retail trade in small rectangular paper packages, each package containing a label designating the size or sizes of the contained needles, with the name and trade-mark of the manufacturer, the number of needles, 25 and various other data.

In retail stores articles of this character are usually contained in and dispensed from an ordinary sliding drawer beneath or behind the sales counter, the drawer being subdivided 30 into a number of open top compartments in which the packages are distributed according to the sizes or makes of the needles, each compartment containing needles of a certain size or make. This 35 manner of and means for housing and dispensing small articles of this nature has at least two defects or drawbacks, which it is the object of my present invention to overcome. In the first place, when the compartments 40 are completely filled the individual packages are usually disposed in upright position and in closely packed arrangement therein, the width of each compartment being such as to just fit the width of the packages. After several of the packages have been removed, the remainder will fall down and lie flat, and in that position, are difficult 45 to remove with the thumb and finger. In the second place, when the drawer is opened, all of the compartments are exposed, and in replacing the packages within the compartments mistakes are easily made, and in a short time the various sizes and makes become more or less mixed up.

50 With these defects in mind, I have de-

vised the commodity cabinet embodying the present invention, which has for its principal objects, to provide a holder or container for articles such as needle packages, containing individual compartments wherein the individual packages will always be equally easy of withdrawal and wherein their positions will not be changed and rendered less accessible after part of the packages have been withdrawn; to provide 55 a cabinet of the character specified of such a nature and construction as to render it practically impossible to accidentally replace packages in the wrong compartments; to provide a cabinet of the character specified 60 wherein the individual compartments will all be normally closed, and will automatically close by gravity from open position when released; to provide a cabinet of the character specified wherein each of the receptacles or compartments can be opened 65 only by tilting the same to open position, and wherein means are provided to limit the extent of tilting movement so that the 70 articles cannot accidentally slip or slide out 75 of the compartment or shift their position in the latter; to provide a cabinet of the character specified combining a maximum of compartments having the advantages 80 above enumerated in a minimum of space; 85 and, generally, to provide a simple, inexpensive and handy cabinet for the containing and dispensing of small articles of merchandise, which may be made from sheet 90 metal in light and durable form, and which is well adapted to display advantageously 95 to both the dealer and the customer sample identifying packages which are attached to the upper wall of each compartment.

Other objects and attendant advantages 95 of the invention will be apparent to those familiar with articles of this general nature from the following detailed description taken in connection with the accompanying drawing in which I have illustrated one 100 practical embodiment of the invention, and wherein—

Figure 1 is a perspective elevation of my improved commodity cabinet, designed in this instance, to contain articles such as 105 packages of plain or sewing machine needles;

Fig. 2 is a vertical cross section of the same from the front to rear;

Fig. 3 is a cross section through the upper 110

portion of one of the receptacles or holders, showing a simple device for fastening a sample identifying package thereto; and

Fig. 4 is a horizontal cross section through 5 one of the individual holders or receptacles.

Referring to the drawing, 5 designates the front wall, 6 the rear wall, and 7 the side walls of a rectangular supporting frame or casing resting on four corner legs 9. 10 These parts as shown are preferably made of sheet metal, including the legs 9, which latter are conveniently attached to the side and end walls by means of integral marginal tongues or lugs 10 on the edges of the legs 15 which pass through and are bent inwardly against the inner sides of the side and end walls, thereby uniting the latter to each other and to the legs. Sufficient stiffness and rigidity is imparted to the frame by forming 20 inturned flanges 11 on the lower edges of the side and end walls. On the upper edge of the front wall 5 there is preferably formed a narrow oblique lip 5' which forms a stop or rest for the forwardly projecting portions 25 of the top walls of the individual receptacles hereinafter described, and on the upper edge of the rear wall 6 is a similar oblique lip 6'. Extending between the side walls 7, in the 30 double row construction herein illustrated, is a partition wall 13 parallel with the front and rear walls 5 and 6, and supported at its lower edge by a foot flange 14 resting on the foot flanges 11 of the side walls 7. The ends of the partition 13 have tongues 15 extending 35 through slits in the side walls 7 and bent to lie flat against the latter, whereby the wall 13 is maintained rigidly in position. The wall 13, like the front wall 5, is provided at its upper edge with a narrow oblique lip 13' forming a stop or rest for the forwardly 40 projecting portions of the rear row of receptacles.

Mounted in and extending between the side walls 7, a short distance in advance of 45 the intermediate and rear walls 13 and 6, are a pair of hinge-rods 17, on which are hinged a plurality of individual holders or receptacles for the packages. As these receptacles are all alike, a description of one will suffice 50 for all. Each receptacle, in the form herein shown, is cut and pressed into shape from a single blank of sheet metal, and comprises parallel side walls 18 having inwardly bent rear flanges 19 the edges of which meet, together forming the rear wall, similar bottom flanges 20, the edges of which meet to form 55 the bottom wall, a top wall 21 having a rear downwardly inclined extension 22 and a substantially horizontal forward extension 23; the front end of the receptacle being open. 60 On the edges of the rear extension 22 are depending flanges 24 through which is passed the hinge-rod 17, and on the forward extension 23 are narrow depending flanges 25 65 which, in the closed position of the recep-

tacle, rest upon the narrow lip 5' or 13' of the frame.

These individual holders are mounted side by side in the supporting frame or casing, and are all normally in the closed position 70 shown in Fig. 1 and at the left of Fig. 2 by reason of their gravity effect. In this closed position the open front ends of the receptacles lie behind and are covered by the frame walls 5 and 13. The individual packages of needles indicated at 26 in Fig. 2, are disposed in each receptacle in superposed relation in the fashion indicated at the left of Fig. 2, each receptacle containing packages of identical goods. In order to conveniently identify the contents of each receptacle without opening the latter, a sample package is secured to the top wall of the receptacle; and a convenient means for attaching such sample identifying package is 80 shown in Figs. 1 and 3 and consists of small prongs or fingers 27 cut and pressed upwardly from the metal of the top wall, and bent over the edges of the sample package 85 26' in the fashion clearly shown. 90

In the use of the cabinet, assuming that it has been loaded or charged with uniform packages containing needles of different sizes or assorted sizes, each receptacle containing packages of the same size or assortments, the dealer identifies the proper receptacle by a glance at the sample or identifying package 26', passes his thumb beneath forward extension 23, tilts the receptacle up to the position illustrated at the 100 right in Fig. 2, withdraws the topmost package, and then lets the receptacle drop to closed position. If the package withdrawn is of the wrong size, or for any other reason is not accepted by the customer, the dealer is 105 not likely to accidentally return it to the wrong receptacle, because all the receptacles are closed and he must first open the right receptacle in order to replace it; and in doing this he is guided by the sample or 110 identifying package on the top wall of the correct receptacle. It will also be obvious that as the individual packages are withdrawn, the remaining packages retain their original positions and cannot fall into more 115 or less inaccessible positions within the receptacles. Furthermore, since all of the receptacles are normally maintained in closed position, and when opened returned to closed position, by gravity, the packages at all 120 times are protected from dust and dirt.

When any receptacle in the front row is opened, the forward edge of the extension 125 23 of the receptacle lying directly in the rear thereof forms a stop to limit the opening movement; and when any receptacle of the rear row is similarly opened the lip 6' on the upper edge of the rear wall 6 forms a similar stop to limit its opening movement. These limiting devices are such that the re- 130

ceptacle cannot be opened to a position in which it will remain at rest in open position, but must necessarily drop to closed position by gravity the moment the receptacle is released. This is an important feature and advantage of the present invention, because insuring against accidental mixup of the packages in the different receptacles and preventing access of dust and dirt to the latter.

I believe that the structure, mode of use, and advantages of the present invention will be clear from the foregoing description of its structure and method of manipulation.

Manifestly, minor changes of detail may be made without altering its essential character or sacrificing any of the advantages inherent therein. Hence, I reserve all such variations and modifications as fall within the spirit and purview of the appended claims.

I claim—

1. A commodity cabinet of the character described, comprising a supporting frame having a wall extending between opposite sides thereof, and a plurality of commodity receptacles disposed side by side between said sides of the frame, each of said receptacles having top, bottom, side and rear walls and a front opening lying behind said frame wall, said receptacles being hinged at their rear ends so as to tilt upwardly and thereby expose their front openings above said frame wall.

2. A commodity cabinet of the character described, comprising a supporting frame having a wall extending between opposite sides thereof, and a plurality of commodity receptacles disposed side by side between said sides of the frame, each of said receptacles having top, bottom, side and rear walls, and a front opening lying behind said frame wall, said receptacles being hinged at their rear ends so as to tilt upwardly and thereby expose their front openings above said frame wall, and a transverse ledge on said frame above and in rear of the hinges of said receptacles for limiting the extent of upward tilting movement of the latter.

3. A commodity cabinet of the character

described, comprising a supporting frame 50 having a wall extending between opposite sides thereof, and a plurality of commodity receptacles disposed side by side between said sides of the frame, each of said receptacles having top, bottom, side and rear walls 55 and a front opening lying behind said frame wall, said receptacles being hinged at their rear ends so as to tilt upwardly and thereby expose their front openings above said frame wall, and the top walls of said receptacles 60 being extended forwardly of their front openings and resting upon the upper edge of said frame wall.

4. A commodity cabinet of the character described, comprising a rectangular supporting frame having substantially vertical front and side walls and corner legs, a hinge rod extending between said side walls parallel with said front wall, and a row of commodity receptacles pivoted at their rear 65 ends on said hinge rod, each of said receptacles having an open front end lying behind the front wall of said supporting frame, and the top walls of said receptacles being extended forwardly of their open front ends 70 and resting upon and overhanging the top edge of the front wall of said supporting frame, whereby each of said receptacles is normally held closed by gravity and may be tilted upwardly to expose its open front 75 end.

5. A commodity cabinet of the character described, comprising a rectangular supporting frame having substantially vertical front and side walls and corner legs, a hinge 85 rod extending between said side walls parallel with said front wall, and a row of commodity receptacles disposed side by side between said side walls, each of said receptacles having top, bottom, side and rear walls 90 and an open front end lying behind the front wall of said supporting frame, and the top walls of said receptacles having downwardly inclined rear extensions pivoted on said hinge rod and forward extensions resting upon and overhanging the top edge of the front wall of said supporting frame.

JAMES H. BOYE.
